Filed Aug. 14, 1935.

Fig. 1.

A technical drawing of a mechanical assembly. It features a rectangular frame with a chain running across it. On the left side, there is a vertical support with three circular components. On the right side, there is another vertical support with two circular components. A chain connects the two vertical supports. The drawing is labeled 'Fig. 2' at the top left.

VEHICLE STRUCTURE

William M. Sheehan, Merion, Pa., assignor to
General Steel Castings Corporation, Granite
City, Ill., a corporation of Delaware

Application August 14, 1935, Serial No. 36,050

13 Claims. (Cl. 105—364)

This invention relates to railway vehicles and particularly to vehicles intended for industrial service.

Cars in certain types of service, such as in mines and about industrial plants, are frequently constructed with their wheeled axles relatively close together and spaced substantially inwardly from the ends of the vehicle to facilitate passage over tracks having sharply changing grades. If a plurality of the vehicles were coupled together by means of ordinary draft devices secured to the ends of the cars, the humps and depressions resulting from the grades, and the substantial overhang of the bodies beyond the wheels, would cause the bodies to interfere, resulting in binding or derailment. On existing types of cars, this is avoided through the medium of a hooked bar pivoted on the exterior of the car side wall near the center of the car. The hook at the other end, which is not free to move vertically, is anchored to the same connection, thus equalizing the load on the pivot pin. The hooks extend the full length of the car and as the overall width of the car usually is limited by clearance conditions, the arrangement described results in reducing the inside width of the car with a consequent reduction in capacity.

The main object of the present invention is to eliminate the above-mentioned interference between vehicles and increase their capacities by relatively simple and inexpensive means.

Another object of the invention is to transfer the draft forces in cars of this type from vertically movable coupling elements through the car framing rather than through the car side walls. The framing usually is of heavier construction than the side walls and is better adapted to withstand draft forces than the side walls.

The invention is applicable particularly to mine cars in which maximum body capacity is desirable.

A more detailed object is to provide a vehicle draft connection capable of movement transversely of its axis, relative to the vehicle body, without restricting the capacity of the vehicle.

These objects and others are attained substantially by the structures illustrated in the accompanying drawing, in which—

Figure 1 is a half top view of a mine car embodying the invention.

Figure 2 is a side view of the same, a part being broken away for clearer illustration.

Figure 3 is a partial end view of the mine car body.

Figure 4 is a detailed horizontal section taken on the line 4—4 of Figure 2.

Figure 5 is a diagrammatic view showing a pair of cars coupled together.

The car illustrated includes body side and end walls 1 and 2, of steel sheets, and an under-construction comprising an integral casting 5 forming a seamless bottom web with upstanding sides. The body walls are reinforced with framing members comprising vertical side posts 3, corner posts 3a, and corner posts 12—13. A horizontal reinforcement 4 extends around the top of two sides and one end of the car body. The other end of the car body is open and is provided with a dumping door 11 and door locking mechanism 11a, the door being supported from the enlarged corner posts 12—13 by the hinge element 11b, whereby these posts function as door hinge posts as well as for reinforcing the doorway to resist bulging.

The under-construction casting has upstanding sides recessed for wheels 6 which are mounted on stub axles 7. The ends of the under-construction casting mount buffers 8 and have safety draft hooks 10 located at the centers of the car ends. The upstanding sides of the under-construction casting are deepened substantially near each end of the car to form brackets 30 and 31, and stationary draft hooks 9 are formed integral with the left hand brackets 30. These hooks are disclosed in my copending application Serial No. 668,258, filed April 27, 1933.

The composite corner post at the right hand end of the car comprises a pair of Z-bars 12 and 13 with their outer flanges overlapping and their inner flanges secured to the body side wall 1 and extending the full depth of bracket 31 to which they are secured.

The web portion of Z-bar 13 is vertically slotted, as at 14, for accommodating the shank portion of a draft device 15 having a hook 16 at its outer end with its tip portion offset outwardly to facilitate attachment of a draft chain. The inner portion of the draft device is vertically enlarged, as at 17, and receives a pair of vertically spaced bearing shafts 18 and 19 rotatably mounting the pairs of rollers 20 and 21. The upper, larger rollers 20 fit relatively closely between the spaced web portions of Z-bars 12 and 13, and the lower, smaller rollers 21 bear against the innermost Z-bar 12 only. Rollers 20 and 21 serve as anti-friction bearings cooperating with track-forming members 12 and 13 to facilitate relative vertical movement of hook device 15. The rollers also function to stabilize the movable hook vertically.

as well as transversely. Vertical movement of the draft hook is limited at the top and bottom by stops 22 and 23. Sliding shoes or other bearing means may be substituted for the rollers.

5. Longitudinal draft forces are transmitted from hooks 15 and corner posts 12-13 direct to the under structure casting 5, which is a rigid structure substantially stronger than the sheet metal superstructure and well adapted to transmit the 10 longitudinal forces from movable hook 16-17 at one end of the car to the fixed hook 9 at the other end of the car, thus relieving the car side walls of any draft forces and eliminating the necessity of continuous draft members in addition 15 to the car framing.

Figure 5 shows a pair of cars 24 and 25, located upon a section of track of sharply changing grade and coupled together by side chains 26 secured to the stationary hook 9 on the car 24, and the 20 vertically movable hook 16 on the car 25. The chain 26 has pulled hook 16 on car 25 above its lowest position.

Clearance requirements limit the width of the car over the outer face of the Z-bar corner post 25 structure and the width of this post structure transversely of the car brings the adjacent portion of the side wall a substantial distance inwardly from the maximum width which would be obtainable but for the corner post structure. 30 To increase the capacity of the car, the side wall is inclined outwardly at the rear of the corner post structure towards the next adjacent side post 3 which is substantially shallower than the corner post. Hence the major portion of the side 35 wall is located a maximum distance from the longitudinal center line of the car and the capacity of the car is increased accordingly.

The weight of the long draft members previously used is avoided, as are the unfavorable 40 features attending the mounting of these hooks on the middle portion of the car wall at a substantial distance above the underframe.

The cars may be coupled closer together than would be possible where both draft connections 45 are vertically immovable, without danger of interference between the adjacent upper corners of the car body when passing over sharply changing grades of increasing slope.

The movable draft hooks are preferably located at one end only of the car, as illustrated, 50 but these may be provided at both ends, if desired, and a single movable hook may be provided at the center instead of the pair of side hooks shown.

55 The broad features of the invention may be embodied in a draft connection arranged to move horizontally instead of vertically to facilitate passage over tracks having sharp horizontal curves. Obviously, the invention may be applied 60 to other types of railway vehicles, the mine car shown in the drawing being merely for the purpose of illustration.

Other modifications may be made in the illustrated structures without departing from the 65 spirit of the invention and the exclusive use of all such modifications coming within the scope of the appended claims is contemplated.

What is claimed is:

70 1. A vehicle body including an underframe and an upright corner post member having a bearing for mounting a vertically movable draft connection and for transmitting longitudinal forces from said connection to the remainder of the vehicle.

75 2. In a vehicle, corner posts at opposite sides of one end of the vehicle, each post having trans-

versely spaced bearing tracks, and a pair of upwardly and downwardly movable draft connections slidably mounted on said tracks for transmitting longitudinal forces to the vehicle from an adjacent vehicle.

3. In combination, a vehicle body framing having an upright bearing track at each side of the vehicle, and draft connections permanently assembled with said framing and movable upwardly and downwardly along said tracks for transmitting longitudinal forces to and from the vehicle.

4. In a vehicle, an angular corner post member at one end having a transverse part forming a bearing track, and a draft device mounted on 15 said vehicle and movable along said member and including an anti-friction element having a bearing on said transverse part for transmitting longitudinal forces therethrough to the vehicle.

5. In a vehicle, a body framing, a relatively 20 stationary draft connection at one end of said framing, a bearing track at the other end of said framing, and a draft connection mounted on and movable upwardly and downwardly along said track for normally transmitting draft forces 25 therethrough to the vehicle at various levels.

6. In combination, a vehicle body, a vehicle upright corner post structure including a part facing longitudinally of the vehicle, and a draft connection mounted on said structure and extending 30 through said part and movable vertically along said part for transmitting draft forces therethrough to the vehicle body.

7. In a vehicle of the class described, a side 35 wall having a restricted end portion offset inwardly of the vehicle, and a vertically movable draft element mounted on the exterior of said end portion and located in the space afforded by the offset between said end portion and the plane of the major portion of said wall.

40 8. In a vehicle of the class described, a body side member, a draft element mounted on said member to move vertically along the same, the side wall of the vehicle at the rear of said element being inclined outwardly toward the longitudinal plane of the outer portion of said member to increase the capacity of the vehicle body without increasing its over-all width across said member.

45 9. In a vehicle of the class described, a rigid, 50 longitudinal force transmitting under-structure, relatively light superstructure side walls mounted thereon, a corner post on said superstructure secured to said under-structure, and a draft device 55 on said corner post above its connection to said under-structure, the connection between said corner post and under-structure being constructed and arranged to transmit a substantial portion of the longitudinal forces received from an adjacent vehicle directly to said under-structure and vice versa.

60 10. In a vehicle of the class described, an underframe of relatively heavy construction, a superstructure of relatively light construction, a corner post connecting said underframe and superstructure, and a draft device mounted on 65 said corner post to slide vertically thereon and arranged to transfer draft forces from another vehicle to said corner post, there being a connection between said corner post and said underframe constructed and arranged to transmit a substantial part of such forces through said underframe to the other end of the vehicle.

70 11. In a vehicle of the class described, an underframe comprising a one-piece web with an 75

upstanding side, relatively light superstructure mounted on said side, a portion of said side being deepened to form a bracket, a corner post mounted on said bracket and extending upwardly therefrom, and a draft device mounted on said corner post to slide vertically along the same above the level of said underframe, the connection between said post and bracket being constructed and arranged to transfer a substantial portion of the longitudinal forces received from another vehicle between said post and side.

5. 12. In a vehicle of the class described, a post adjacent a corner of the vehicle, an upright wall structure on the inside of said post, and inclined 10 outwardly therefrom longitudinally of the vehicle,

and means on said post for attachment of a draft device and located inwardly of the same general vertical plane as the outer portion of said wall.

13. In a vehicle of the class described, a relatively heavy underframe, a relatively light 5 superstructure side wall, a corner post anchored to said underframe and projecting upwardly therefrom, a device on said post for a coupling chain, said post and its connection to said underframe being arranged to transmit draft 10 forces from said device to said underframe independently of said superstructure side wall, said device being movable along said post above the level of said underframe.
